UNITED STATES PATENT OFFICE.

ALBERT F. TUCKER, OF AUBURNDALE, MASSACHUSETTS.

TELEGRAPH-KEY.

SPECIFICATION forming part of Letters Patent No. 479,859, dated August 2, 1892.

Application filed March 24, 1892. Serial No. 426,236. (No model.)

To all whom it may concern:

Be it known that I, ALBERT F. TUCKER, of Auburndale, in the county of Middlesex, State of Massachusetts, have invented certain new 5 and useful Improvements in Telegraph-Keys, of which the following is a description sufficiently full, clear, and exact to enable any person skilled in the art or science to which said invention appertains to make and use 10 the same, reference being had to the accompanying drawings, forming part of this specification, in which—

Figure 1 is a side elevation of my improved key; Fig. 2, a top plan view of the same, and 15 Fig. 3 a sectional view illustrating details.

Like letters of reference indicate corresponding parts in the different figures of the drawings.

My invention relates especially to a self-closing telegraph-key. Much difficulty is frequently experienced from the fact that switches of telegraph-instruments in a line are accidentally left open, incapacitating the line for work until such switches are closed.

25 In my improved device the key is provided with an automatic switch, whereby the circuit is normally closed when the instrument is not in use.

The nature and operation of the improvement will be readily understood by all conversant with such matters from the following explanation.

In the drawings, A represents the table, upon which the instrument is mounted. The 35 ordinary binding-posts d d^2 for the conducting-wires pass through the table in the usual manner and are respectively connected with connecting-strips b b^2 on the face of the table, said strips being preferably semi-elliptical, 40 as shown, and out of electrical contact with each other. In lugs f^2 on the plates b b^2 the key-shaft g is journaled, said shaft being provided with the ordinary tension-nuts. The bearing of the shaft in the lugs f^2 is insulated at h , Fig. 3, from the plate b^2 .

45 The key B is mounted on the shaft g and is of the ordinary general construction. Its short arm is provided with the usual adjustable

contact-point i , which normally is in engagement with the plate b . The long arm of the 50 key has an adjustable screw j , against which a push-spring k bears, tending to elevate said arm. A projection m is formed on the plate b , and a contact-point p on the long arm of the lever is in position to be engaged therewith in 55 operating the key in the usual manner.

A switch C comprises a lever pivoted in laterally-projecting lugs q on the key. The long arm of the lever projects from the finger-piece r of the key and is provided with a lip 60 t , which may be readily engaged by the fore-finger of the operator. The opposite arm of the switch engages the lug f^2 on the plate b^2 and is held normally in contact therewith by a push-spring v on the key B.

65 When the instrument is not in use, the circuit is closed, the current passing through the post d , plate b , contact-point i , key B, switch C, and plate b^2 .

In manipulating the key the operator by 70 pressing the fore-finger against the lip t of the switch throws said switch laterally, disconnecting said point w from the lug f^2 , breaking the circuit.

The key in other respects is operated in 75 the usual manner, the circuit being closed by depressing the key contacting the points p m and broken by the elevation of the key.

Having thus explained my invention, what I claim is—

80 1. In a telegraph-instrument, two disconnected plates respectively in electrical contact with the line wires, a telegraph-key pivoted on said plates and insulated from one thereof, contact-points on said key in position to alternately engage said plate, and a spring-pushed switch pivoted to the key and normally in contact with said insulated plate, substantially as described.

85 2. In a telegraph-instrument, the combination of the plates, as b b^2 , respectively connected with the contact-wires, and the key B, insulated from the plate b^2 of the switch C, normally in electrical contact with the plate b^2 , substantially as described.

90 3. In a telegraph-instrument, the combina-

tion, with the plates b b^2 and mechanism for attaching them, respectively, to the conducting-wires, of the key B, pivoted on said plates and insulated from one thereof, contact-
5 points on said key for alternately engaging said plates, and the spring-tensioned switch C, pivoted to said key and normally in contact

with said insulated plate, substantially as described.

ALBERT F. TUCKER.
